UNITED STATES PATENT OFFICE.

ROBERT G. BROWN, OF BROOKLYN, ASSIGNOR TO THE STANDARD MULTIPLEX TELEGRAPH COMPANY, OF NEW YORK, N. Y.

TELEGRAPHY.

SPECIFICATION forming part of Letters Patent No. 449,897, dated April 7, 1891.

Application filed June 27, 1887. Serial No. 242,602. (No model.)

To all whom it may concern:

Be it known that I, ROBERT G. BROWN, of Brooklyn, in the county of Kings and State of New York, have invented an Improvement 5 in Telegraphy, of which the following is a specification.

This invention relates to that class of telegraphy in which there are two synchronously revolving trailers, one at each station and connected by the main line, and two or more local lines connected with the main stations, so that the main line can be made use of by either of the parties having instruments in the local lines. The trailers in traveling over 15 the segments allotted to the respective local lines connect together corresponding local lines of the two main stations two or more times in each revolution of the trailers, and a reference is hereby made to Letters Patent 20 No. 358,379, granted February 22, 1887, to the Standard Multiplex Telegraph Company as my assignees, and also to the prior patents named in the same, for a description of the mode of operation of the synchronous multiplex telegraphs of the character to which my present invention relates. In all telegraphs of this general character these synchronous trailers pass with great rapidity from one contact-segment to the next, and although electric 25 operations may often be regarded as instantaneous I have discovered that in telegraphs of this character time enters as a necessary element to be considered in rendering the operations perfect. To illustrate, suppose a current passes to the trailer and upon the line from one segment, that current must reach the distant instrument and perform its duty therein, and the line be discharged before the trailer comes into contact with the next segment. 30 Otherwise the static discharge of the line will pass to some other telegraphic apparatus over a different local line and make confusion or interfere with the proper operation of the other local line.

40 In telegraphic operations it is a well-known fact that after a line is charged with an electric pulsation and the battery-circuit broken there is a static discharge to ground.

A portion of the static current flows to the distant station, and the larger portion discharges to the ground at the sending-station. This static discharge in practice is a source of inconvenience in multiplex telegraphy, and I provide a special connection for the discharge of the same, and utilize that discharge 50 for making the record at the sending-station, and although my improvements are specially available in connection with transmitters and printing receiving-instruments such as shown in my aforesaid patent No. 358,379, and in patents Nos. 364,893 and 364,894, granted to me June 14, 1887, still I do not limit myself to any particular character of transmitting and receiving instruments in the local lines connected with the synchronous trailers and the 55 main line.

In the drawings I have shown in Figures 1, 2, 3, and 4 diagrams illustrative of my improvement, and in Fig. 5 a diagram illustrative of my improvement as applied with the instruments shown in my patent No. 358,379.

Let K, Fig. 1, represent the rotating shaft of the synchronous instrument at one end of the main line, and A the arm of the trailer a' , said trailer passing over the pairs of segments 1^1 2^2 , &c., and it is to be understood that these segments are connected up so that the desired number of pairs are allotted to each local line. I have shown sixty such segments and six pairs of segments allotted to one local line, so that five local lines could be used with this instrument.

F is the electro-magnet, which is brought into action by the transmitting devices, and G is the armature of the same, and the main 85 battery MB is connected to the back stop g and the ground to the front stop 12, and the armature G is connected to the segments 1 by the wire 13, and upon the armature G is an insulated spring-finger f' , and f^2 is the stop 90 for the same, from which stop f^2 is a ground-circuit 4, containing an adjustable resistance Rh. From the insulated spring-finger f' a wire 16 connects to the ground-circuit 17 from the segments 1^1 , in which circuit is the helix 95 of the main line or receiving-relay H, which

receiving-relay acts in connection with any desired receiving apparatus.

It will now be understood that when the armature of the transmitting-magnet F is on its back contact g the battery MB is connected by g G and 13 to the segments 1, and that a current will pass over the line when the trailer a' is passing over that segment, and as the trailer a' passes off the segment 1 and onto the segment 1^x the static discharge takes place through the segment 1^x and the receiving-relay H; but as the static discharge at the transmitting-station generally exceeds the current at the receiving-station I provide the second path for the same through the wire 16, insulated spring-finger f' , stop f^2 , and adjustable resistance Rh to the ground, thereby utilizing so much of the static discharge as is necessary to operate the receiving-relay H at the sending-station and allowing the remainder to freely escape to ground through the adjustable resistance Rh. Hence by the time the trailer a' reaches the segments of the next pair of segments for another local line there will not be any current or static discharge to pass into such second local line.

It is a well-known fact in telegraphic operations that an electric current sent over a line is retarded according to the length and nature of the line. Hence when a current is pulsated over a long line of high capacity, as when the trailer at the sending-station is passing over its segment 1, the current does not arrive at the receiving-station until the trailers are passing onto their segments 1^x . At the receiving-station the armature G is held in contact with the grounded stop 12, and the contact of f' with f^2 is broken, so that all the current arriving over the main line from the transmitting-station passes from the segment 1^x through the relay H to ground, and this takes place at exactly the same moment that the static discharge at the sending-station is passing to ground through the relay H and resistance Rh at that station. Hence the relays H at both stations are actuated at the same moment.

In Fig. 2 the same parts are shown as in Fig. 1, with the addition of the relay H' and a local circuit, in which is included the battery I and magnet C', corresponding to the parts shown in Fig. 4 of my aforesaid patent, No. 358,379, and for the objects and operations as therein set forth, it being understood that the relay H' is of a comparatively low resistance and constructed with short cores, the object being to provide a path to ground by which the static-discharge current which actuates this relay may not be unnecessarily retarded in escaping to ground.

When the instrument shown in Fig. 2 is receiving a message, the armature G is closed on 12 and the relay H receives the incoming current; but when this instrument, Fig. 2, is

acting as a transmitter the armature G is in contact with g and the static discharge acts in H'.

In Fig. 3 the same parts are shown as in Fig. 2, with the addition of an adjustable resistance Rh, which permanently shunts the magnets of the relay H', the object being to provide an additional path by which the static-discharge current (which actuates the relay H') may be less retarded in escaping to ground.

In Fig. 4 I have shown my present improvements in connection with a reversing-relay RR, polarized tongue 14, contacts 30 and 31, and reversing-batteries, such as shown in my patent No. 364,893, the parts connected with such reversing-relay and the mode of operation being fully set forth therein.

In the application of the present improvements to the devices set forth in my said patent, No. 364,893, the current of the main battery MB is through stop g , armature G, wire 13 to segments 1, and is pulsated over the main line by the trailer a' passing over those segments, and the relay RR at the sending-station is actuated by a portion of the static-discharge current passing from the segments 1^x through the relay-magnets RR to ground, and the two adjustable resistances Rh from the wires 17 and 17^a , with their respective contact-stops f^2 , insulated spring-finger f' , and wire 4, cause the proper proportion of the static discharge to act in the reversing-relay RR and give a free discharge for the remainder to ground by the wire 4. At the receiving-station, the armature G being held in contact with the stop 12, the contact with f' and the two stops f^2 is broken, so that all the current arriving over the line from the sending-station passes from segment 1^x through reversing-relay RR to ground, and this takes place at exactly the same time that the static discharge is actuating the corresponding relay at the sending-station.

In Fig. 5 the present improvement is represented in connection with the devices shown in Fig. 4 of my aforesaid patent, to which a reference is hereby made. In my patent, No. 446,424, dated February 17, 1891, each operator is provided with one or more pairs of segments, such segments being arranged side by side. Transmitted currents are sent out on the first segment, while received impulses are received from the second segment. For instance, in Fig. 5 I have shown the operator with one pair of adjoining segments marked 2 2^x . As set forth in that application, the battery-current passes to line when the trailers at the two stations are upon the corresponding segments marked 2, and when the trailers come upon the corresponding segments marked 2^x , the line having been disconnected from the battery when the trailers passed from the segments marked 2, discharges itself, and thus produces the proper signal. The purpose of the arrangement shown in Fig. 5 is to adapt

the synchronous system to long lines or to the retardation of the line, as set forth in my application Serial No. 194,302. Where single segments are used on a line of sufficiently-high 5 resistance, the current from the battery sent in on one segment does not have time to manifest itself at the distant station upon the corresponding segment while the trailers are yet upon such segments.

10 In order to adapt my printers (shown in Patent No. 358,379) to the system set forth in my present application, I connect the first segment of the pair or pairs—that is, segment 2, as shown in Fig. 5—direct to the armature 15 G, which is normally on its grounded front post. The other segment 2^x is connected permanently through the relay H to the earth. When a key is depressed, the armature G goes to its back stop, thus connecting the 20 main battery MB directly with the segment 2. As the trailer passes over the segment, the current enters the line. As the trailers pass onto segments 2^x , the discharge takes place at each end of the line through the 25 relays H, which are therefore operated at exactly the same moment. A piece of ivory or other material may be placed between the segments 2 2^x to prevent the current bridging.

I claim as my invention—

30 1. The combination of the synchronously-actuated trailer, one or more pairs of adjacent message-segments, the transmitting-magnet F and armature G, the main battery, a connection between the first segment of each 35 pair and the armature G, a relay, and an electric connection from the second segment of said pair through the relay to earth, substantially as set forth.

2. The combination, with the synchronous 40 trailer and the segments connected in pairs, of a transmitting magnet and armature, a main battery connected through the armature to the first segment of the pair, a receiving-relay, and a connection to the second segment of 45 such a pair, and a shunt and resistance around the receiving-relay, substantially as set forth.

3. The combination, in a synchronous telegraph, of a trailer at each end of the main line, segments in pairs, a transmitting-instrument 50 connected to the first segment of the pair, and a receiving-instrument connected to the second segment of the pair, and an uninterrupted connection from the second segment of such pair to the relay and to the ground, substantially as set forth.

55 4. The combination, with synchronous trailers and segments in pairs, of a transmitting magnet and armature, an insulated spring-finger thereon, a receiving-relay and an adjustable resistance, a main battery, a connection between the first segment of the pair and the armature, a connection between the second segment of the pair and the receiving-relay and ground and with the spring-finger, and 60 a stop for the spring-finger and connection

therefrom to the adjustable resistance and ground, whereby the current is sent to line through the first segment of the pair and the static discharge passes through the second segment of the pair and divides, a portion 70 going through the receiving-relay and the remainder through the spring-finger and resistance, substantially as specified.

5. The combination, with a synchronous trailer and its segments in pairs, of a transmitting magnet and armature, a main battery connected with the back stop of such armature, a connection between the armature and the first segment in the pair, a reversing-relay and connections to the second segments 80 of the pairs, an insulated spring-finger on the armature, ground connections, and a resistance in a shunt-circuit between the stop of the spring-finger and the reversing-relay, substantially as set forth. 85

6. The combination, with a synchronous trailer and its segments in pairs, of a transmitting magnet, armature, and battery, and a receiving-relay having a short core, and a ground connection to the said receiving-relay 90 and to the second segment in the pairs, substantially as set forth.

7. The combination, with the synchronous trailer and its segments in pairs, of a receiving-relay connected to the second segment of 95 the pair, and a shunt containing a resistance, substantially as set forth.

8. The combination, with the synchronous trailer and its segments in pairs, of a transmitting magnet and armature, and two receiving-relays, and connections, substantially 100 as set forth, whereby one relay is actuated by the current received from the distant station and the other relay is actuated when the instrument is transmitting by the static discharge, substantially as set forth. 105

9. The combination, with the synchronous trailer and its segments in pairs, of a reversing-relay and connections to two of the second segments in the pairs of segments, substantially as set forth. 110

10. The combination, with the synchronous trailer and its segments in pairs, of a reversing-relay and connections to two of the second segments in the pairs of segments, and 115 shunt connections containing resistances, substantially as set forth.

11. The combination, with a synchronous multiplex transmitting telegraph-instrument having circuit-closing segments arranged in 120 pairs, of a receiving-instrument at the sending-station, and circuit-connections to the second segments in the pairs, substantially as set forth, whereby the static discharge from the line is directed through the second segment to the receiving-instrument, substantially as specified. 125

12. The combination, with a synchronous multiplex transmitting telegraph-instrument having circuit-closing segments arranged in 130

pairs, of a receiving-instrument at the sending-station and electric-circuit connections between the battery and one of the segments in the pairs in the transmitter, and connections from the other segment to the receiver, and also a shunt-circuit to earth and a resistance in the same, whereby the static discharge from the line through the second segment is divided and a portion goes through the resist-

ance and the rest is directed through the receiving-instrument, substantially as specified.

Signed by me this 24th day of June, A. D. 1887.

R. G. BROWN.
